Alice Elma Morrison, 10643 Morcolgro Lane,
Beltsville, Md.

Filed May 6, 1965, Ser. No. 85,141

Term of patent 14 years

(Cl. D58—8)

FIG.1

FIG. 1 is a front elevational view of a bottle embodying my new design;

FIG. 2 is a side elevational view;

FIG. 3 is a top plan view; and

FIG. 4 is a sectional view taken on the line 4—4 of FIG. 1.

The rear is the same in appearance as the front, except for the omission of the dotted line ornamentation on the main body portion.

The dominant features of my design reside in the configuration shown in full lines.

I claim:

The ornamental design for a bottle, as shown and described.
